(57) **CLAIM**

The ornamental design for a E-bike with four display monitors as shown and described.

DESCRIPTION

FIG. 1 is a perspective view of a E-bike with four display monitors showing our new design.

FIG. 2 is a front view of the E-bike with four display monitors of FIG. 1.

FIG. 3 is a rear view of the E-bike with four display monitors of FIG. 1.

FIG. 4 is a right view of the E-bike with four display monitors of FIG. 1.

FIG. 5 is a left view of the E-bike with four display monitors of FIG. 1.

FIG. 6 is a top view of the E-bike with four display monitors of FIG. 1; and,

FIG. 7 is a bottom view of E-bike with four display monitors of FIG. 1.

In the drawings, the broken lines depict environmental subject matter only and form no part of the claimed design.
